Primary Examiner — T Chase Nelson*Assistant Examiner* — Sydney Margaret Parsley*(74) Attorney, Agent, or Firm* — Nitin Kaushik(57) **CLAIM**

The ornamental design for a mesh panel, as shown and described.

DESCRIPTION

FIG. 1 is a front, right, top perspective view of a mesh panel, showing my new design;

FIG. 2 is a rear, left, bottom perspective view thereof;

FIG. 3 is a front elevational view thereof;

FIG. 4 is a rear elevational view thereof;

FIG. 5 is a left side elevational view thereof;

FIG. 6 is a right-side elevational view thereof;

FIG. 7 is a top plan view thereof;

FIG. 8 is a bottom plan view thereof;

FIG. 9 is an enlarged view of detail 9 in FIG. 1;

FIG. 10 is an enlarged view of detail 10 in FIG. 2;

FIG. 11 is a sectional view of 11-11 along the line in FIG. 3;

FIG. 12 is a sectional view of 12-12 along the line in FIG. 3;

FIG. 13 is an enlarged view of detail 13 in FIG. 11;

FIG. 14 is an enlarged view of detail 14 in FIG. 12; and, FIG. 15 is a front, right, and top perspective view thereof, wherein the mesh panel is shown in a condition of use.

The dot dash lines depict the boundaries of the enlargements and form no part of the claimed design. The consistent length broken lines in FIG. 15 represent environmental structure which forms no part of the claimed design.

1 Claim, 15 Drawing Sheets(56)
